UNITED STATES PATENT OFFICE

JOSEPH BERNARD DOYLE, OF MOUNT VERNON, NEW YORK, ASSIGNOR TO JAMES L. HOWARD & COMPANY, OF HARTFORD, CONNECTICUT, A CORPORATION OF CONNECTICUT

DOORCHECK

Application filed November 14, 1928. Serial No. 319,425.

This invention relates to an improvement in door checks, and the disclosure herein, used for illustrative purposes, shows the invention applied to the sliding end door of a railway coach, and to a swinging door, and also shows an adaptation of the invention in the form of a latch.

The general object of the invention is to provide a check for preventing a door from slamming closed, without being stopped a few inches away from the door post.

A further object of the invention is to provide such a device, which, upon the door being arrested, will automatically allow the door to continue its closing movement without interruption.

By so controlling the closing movement of the door, many accidents, such as the pinching of a passenger's hand between the door and post, by reason of the door accidentally slamming shut, or being suddenly closed by the train attendant, may be prevented.

A further object of the invention is to provide a door check which, when the door is closed at not to exceed a certain speed, will not come into operation to check the closing of the door, but which will so check it, when the limit of speed of the closing operation is exceeded, and one which will further operate automatically, both to check the door, and to allow of the subsequent continued closing movement, the action of gravity being taken advantage of to replace the parts in position to allow the closing of the door after the checking has taken place.

Another object is to provide a door check of the type set forth above which will not affect or impede the opening movement of the door, irrespective of the speed of such movement.

With the above and other objects in view, which will more particularly appear as the description proceeds, the invention resides in the construction, combination and arrangement of parts hereinafter more particularly set forth and claimed.

In the drawings,—

Figure 1 represents an elevational view of the end of a railway coach with the invention applied to the sliding door thereof.

Figure 2 represents an enlarged elevational view, partly broken away and partly in section, from the inside of the door looking out therefrom.

Figure 3 represents a top plan view of the disclosure of Figure 2.

Figure 4 represents a view similar to Figure 2 showing the position of the parts in the arrested position of the door, and before the arm has dropped by gravity to allow the continued closing of the door.

Figure 5 represents a top plan view, parts being in section, of the invention applied to a swinging door and its jambs.

Figure 6 represents an elevational view of the arrangement of Figure 5.

Figure 7 represents an elevational view of an adaptation of the invention in the form of a combined stop and latch.

Referring more particularly to the drawings, a railway coach is indicated at A, a sliding end door therefor is indicated at B, the check is indicated generally at C, and the door post is indicated at D.

Modern cars are built of steel, and the invention will be particularly described as applied to the car construction now in general practice, but it is to be understood that the invention is not to be limited to sliding doors or to the particular type of door disclosed, or to the particular construction of such door and its co-operating parts.

An arm 5, which may be counter-weighted at 5', is pivoted at 6 between the sides of the door, extending out through a slotted opening 7, the bottom wall of such slot serving as a rest for supporting the arm normally in horizontal position, and such arm is located preferably near the top of the door so as not to impede free passage through the door-way, or to offer obstruction thereto. The outer end of the arm is preferably rounded as at 8, and at its lower edge inclines gradually downwardly from such rounded portion to provide a cam surface 9, which at 10 bends sharply downwardly and then around to form a nodule 11, the surface of the cam 9 and nodule 11 merging at the curved surface 12. On its upper edge, the arm 5 is formed with a shoulder or stop 13, positioned about

the middle of the cam 9.

even with the portion of the nodule nearest the pivot point 6. The door post D, including the strip 14 flanged to receive the door, usually found thereon, is provided with an opening 15 opposite the arm 5, such opening being of a vertical height somewhat greater than the vertical width of the arm 5, including the nodule and shoulder 13, to allow these parts to pass through the opening as the door moves into closed position. The width of the opening 15 is slightly greater than the horizontal width through the arm, to allow free passage of the arm therethrough.

In operation, normally the door being open, the arm will be in horizontal position shown in Figures 1 and 2. If the door should inadvertently slam shut, or should be closed at too great a speed by the trainman, the cam surface 9, as the arm approaches and enters the opening 15 on the door stop, will, by engaging the lower edge of the opening in the door post start an upward movement of the arm, and as the curved portions 12 and 10 of the cam surface and the nodule engage the edge of the post opening, this upward movement will be greatly accelerated, with the result that the arm will be thrown upward to a position where the shoulder 13 will engage with the material of the door post at and adjacent to the upper edge of the opening therein, as shown in Figure 4, thus checking the closing movement of the door. The door having been checked in its movement, gravity acting upon the arm 5 will cause it to fall, whereupon the upper edge of the shoulder 13 will clear the upper edge of the opening 15 in the door post, the nodule, having passed the edge of the opening, dropping upon the lower wall thereof and thereupon the door is free to continue its closing movement without interruption.

The door may, of course, be gradually closed as the arm approaches the post, at a speed which will allow the arm to ride on its cam surfaces without throwing the arm upwardly, the door thus being capable of being closed without an interrupted movement. If, however, this speed of closing is exceeded either when the door accidentally tends to close, or is purposely closed, the check will come into play and thus stop the closing movement when the door arrives at a position for a few inches away from its post.

The door being closed, it will be observed that the check will not impede the opening movement of the door in any way, this for the reason that the shoulder and the metal adjacent thereto, being as near the pivot as the nearest portion of the cam surface of the nodule, will enter the opening 15 upon the opening movement of the door before the nearest cam surface contacts with the inside edge of such opening. So that even if the opening movement is fast enough to throw the arm upwardly the only thing that could

happen would be for the top surface 16 of the shoulder to strike against the upper wall of the opening 15 as the shoulder passed therethrough. This, however, would offer no resistance to the opening movement.

The pivot 6 for the arm 5 may be in the form of a headed bolt which passes through the side plates of the door and which, on the side opposite the head, receives a nut 6'. The latter may be retained against loss by the cotter pin 17. In assembling the device, the arm may be passed into the door through the opening 7, which may be large enough for this purpose, and the opening in the arm for the reception of the bolt aligned with the openings in the door faces through which the bolt projects. The bolt may then be passed through the aligned openings in the door faces and arm, the nut assembled, and the cotter pin put in place. Of course other methods of mounting and assembly may be used, but this illustrates a simple and effective method of mounting the device.

In the form of the application of the invention to a swinging door, as illustrated in Figures 5 and 6, the arm 5^a may be pivoted as by a rivet or other suitable means 6^a in a support 18 screwed or otherwise secured as at 19 to the face of a swinging door B'. Such support may have a shoulder 20 serving as a rest to hold the arm normally in substantially horizontal position. In this form of the invention the arm may, as illustrated, be not equipped with a counter-weight, since such counter-weight would take up room, and in the type of installation illustrated, it is desirable to have the device as inconspicuous as may be and to occupy a minimum amount of room. To co-operate with the arm, in the manner as heretofore already set forth with reference to the sliding door, the door jamb D' is provided with a bracket 21 secured thereto in desirable manner and provided with spaced arms 22 and 23 positioned apart a distance slightly greater than the vertical width of the arm through the nodule 11' and shoulder 13', to allow these parts to pass between the arms as the door moves into closed position.

If desired the cam surface 9' of the arm may be straight rather than compound as in the form shown for instance, in Figure 2, and may be sufficiently steep to insure of the arm being thrown upwardly when such cam surface strikes the edge of the lower arm 23 of the bracket when contacting therewith at a speed exceeding a given limit. When so thrown upwardly, the shoulder 13' will engage the arm 22 and thus arrest the closing movement of the door, the arm thereupon being pulled down by gravity to allow the door to continue its closing movement, as heretofore set forth in connection with the first form of the invention described.

In the adaptation of the invention in the form of the combined stop and latch, as il-

lustrated in Figure 7, one end 5^b of the arm 5^c may project through an opening in the door B² onto the outside of the door to be engaged by one opening the door, in order to lift the arm, and the opposite end of the arm may be extended as at 5^d to afford a thumb or finger hold on the inside of the door at such opposite end. The extended end 5^b will act as a counter-weight. In this form of the invention, a suitable bracket 18' pivotally supports the arm in position on the door, and the bracket 21' which may be similar to the bracket 21 is carried on the door jamb D². In this type of the invention, however, the nodule 11^a instead of being rounded on its side toward the pivot, as in the other forms of the invention illustrated, is squared on this side to form a shoulder 24, and such shoulder engaging against the inner face of the lower arm 23^a of the bracket, will prevent the door from being opened until the arm is manually raised. Thus in this form of the invention, a latch is combined with the stop feature of the invention, and this latch may be manually lifted from the inside or outside of the door, as the case may be, by a person desiring to pass therethrough. This form of the invention is adapted for use, for instance, on swinging screen doors. Such doors are usually equipped with spring means for closing them. The door stop feature of this form of the invention will effectually arrest the closing of the door at a point spaced from the jamb before it swings entirely closed, the door thereafter closing when the arm drops by gravity, as in the other forms of the invention. The distance at which the door may be stopped from the jamb in the forms of the invention shown in Figs. 5-7 may be adjusted by placing the bracket closer to or further from the edge of the jamb against which the door closes. By thus preventing the door from slamming to, under the action of its closing spring, not only is quieter operation and closing movement of the door secured, but the pinching of anything between the edge of the door and its jamb may be prevented, and thus many accidents, of which children and household pets, for instance, are often the victims, may be avoided.

The bracket of Figs. 5-7 with its spaced arms corresponds in function with edges and walls of the opening in the door post of the form of the invention illustrated for instance, in Figure 2, the space between the arms corresponding to the opening in the door post of that figure; and the door jamb of Figs. 5-7 corresponds in function with the door post of Fig. 2, so that my claims which include the door post, with an opening therein, are intended to include the door jamb and bracket structure of Figs. 5-7 as well.

The foregoing description has been given for purposes of illustrating the invention, and no undue limitations should be deduced

therefrom, but the appended claims should be construed as broadly as permissible, in view of the prior art.

Having thus described my invention what I claim as new is:—

1. The combination with a door and its post, the latter having an opening therein, of an arm pivoted to the door, such arm being provided with a cam surface on its lower edge adapted to engage the lower edge of the opening and to throw the arm upwardly when the door is slammed to, the said arm being provided on its upper edge with a shoulder adapted to engage the upper edge of the opening when the arm is thrown upwardly, said shoulder being located slightly rearwardly of the said cam surface, the opening being of greater vertical dimension than the combined vertical dimensions of the arm including the said cam surface and the shoulder, the opening being of greater horizontal dimension than that of the arm, to permit the arm to pass therethrough, the said arm being adapted, after having been thrown upwardly, to return by gravity to its normal position, thereby allowing the door to move into closed position.

2. The combination with a door and its post, the latter having an opening therein, of an arm pivoted to the door, such arm being provided at its tip with a rounded surface, the arm being further provided with a cam surface on its lower edge adapted to engage the lower edge of the opening to throw the arm upwardly when the door is slammed to, a nodule on the lower surface of the arm, the said cam surface forming a curved joinder between the nodule and the said rounded tip of the arm, a shoulder on the upper surface of the arm adapted to engage the upper edge of the opening to check the door when the arm has been thrown upwardly by the said nodule, the opening being of greater vertical and horizontal dimensions than the arm, including the said shoulder and nodule, to permit the arm to pass therethrough, the arm being adapted to return by gravity to its normal position after having stopped the closing movement of the door.

3. The combination with a door and its post, the latter having an opening therein, of an arm pivoted to the door, such arm being provided at its tip with a rounded surface, the arm being further provided with a cam surface on its lower edge adapted to engage the lower edge of the opening to throw the arm upwardly when the door is slammed to, a nodule on the lower surface of the arm, the said cam surface forming a curved joinder between the nodule and the said rounded tip of the arm, a shoulder on the upper surface of the arm adapted to engage the upper edge of the opening to check the door when the arm has been thrown upwardly by the said nodule, the said shoulder

being adapted to come into contact with the edge of the opening only when a certain pre-determined speed of closing is exceeded, the opening being of greater vertical and horizontal dimensions than the arm, including the said shoulder and nodule, to permit the arm to pass therethrough, the arm being adapted to return by gravity to its normal position after having checked the closing movement of the door.

In testimony whereof I hereunto affix my signature.

JOSEPH BERNARD DOYLE.
